UNITED STATES PATENT OFFICE.

LOUIS STOCKSTROM, OF ST. LOUIS, MISSOURI, ASSIGNOR TO AMERICAN STOVE COMPANY, OF ST. LOUIS, MISSOURI, A CORPORATION OF NEW JERSEY.

DESIGN FOR A BAKING AND WARMING OVEN.

No. 39,235.

Specification for Design.

Patented March 31, 1908.

Application filed January 22, 1906. Serial No. 297,372. Term of patent 7 years.

To all whom it may concern:

Be it known that I, LOUIS STOCKSTROM, a citizen of the United States, residing at St. Louis, in the State of Missouri, have invented a new, original, and ornamental Design for Baking and Warming Ovens, of which the following is a specification, reference being had to the accompanying drawings, forming a part thereof.

In the accompanying drawings, Figure 1,

is a perspective view of my design for baking and warming ovens. Fig. 2, is a side elevation of the same.

I claim—

The ornamental design for a baking and warming oven, as shown.

LOUIS STOCKSTROM.
